[57] CLAIM

The ornamental design for the eyeglasses with built-in watch, as shown and described.

DESCRIPTION

FIG. 1 is a perspective view for the novel design of eyeglasses with built-in watch, having the watch function facing inwardly toward the face of the user; FIG. 2 is a front elevational view of the eyeglasses with built-in watch showing the watch facing exteriorly of the eyeglasses;

FIG. 3 is a top plan view of the eyeglasses with built-in watch design;

FIG. 4 is a rear elevational view of the eyeglasses with built-in watch design showing the watch functions facing inwardly toward the face of the user; and,

FIG. 5 is a side elevational view of the eyeglasses with built-in watch, the side opposite being a mirror image.
